John G. Muller

UNITED STATES PATENT OFFICE

JOHN G. MUELLER, OF DAYTON, OHIO

GRIPPING AND SHOCK-ABSORBING EQUIPMENT FOR RAILWAY TRACKS

Application filed May 3, 1930. Serial No. 449,469.

This invention relates to gripping and shock-absorbing equipment for railway tracks.

It is the object of the invention to provide a device which when applied to railway tracks will grip the rails with a vice-like grip and absorb the strains resulting from heavy train traffic in such a manner that the strains will be distributed throughout the entire device instead of being concentrated at any one point, thereby providing a strong and durable device.

It is also an object of the invention to provide such a device which will be readily adjusted to position the rails to the desired gauge and to positively retain them in fixed lateral relation with each other.

It is also an object of the invention to provide such a device which will be universal in that it may be readily adjusted to rails of varying dimensions without any change in construction; and which will be inexpensive to manufacture, comprising a minimum number of parts capable of being readily assembled.

It is also an object of the invention to provide a casing for the threaded part of the tie rod and insulation surrounding same.

It is also an object of the invention to provide a locking member which will be carried by a housing and grip the top of a rail base.

In the accompanying drawings:

Fig. 1 is a sectional elevation of a railway track with my gripping and shock-absorbing device applied thereto;

Fig. 2 is an enlarged detail sectional view of one rail with my invention applied thereto; Fig. 3 is an enlarged detail sectional view of a rail of larger dimension than the rail shown in Fig. 2 showing my invention applied thereto;

Fig. 4 is a detail view of the locking member taken along the line 4—4 of Fig. 5 and looking in the direction of the arrows;

Fig. 5 is a sectional view of the locking member taken on the line 5—5 of Fig. 4 and looking in the direction of the arrows; and

Fig. 6 is a view of the locking member taken along the line 6—6 of Fig. 5 and looking in the direction of the arrows.

Referring to Fig. 1 of the drawings the opposite rails of the track are indicated by the numerals 1 and 2. A rod 3 extends beneath the rails from a point beyond the outer edge of one rail to a point beyond the outer edge of the opposite rail and is screw-threaded at each end, as shown at 4, to permit of adjusting the rail gripping members. In order to protect the threaded portion of the rod a casing 5 is provided and when the invention is applied to tracks with which electric signals are utilized, insulation, as shown at 6, may be interposed between the rod 3 and the casing 5.

The rail gripping device comprises a housing or outer member 7 and a locking member 8. Referring first to the housing 7, it has an opening 9 to receive the tie rod 3 and a flat upper surface 10 to engage and support the bottom of the rail base. Within the housing 7 are oppositely disposed inclined surfaces 11 and 12, a portion of the surface 12 being cut away, as shown at 13, to save material and thus reduce the cost of manufacture. At the rear of the housing 7, in the bottom thereof, is an opening 14, for the purpose herein-after set forth.

I will now describe the locking member 8, shown in detail in Figs. 4, 5 and 6. Extending through the member is an opening 15 to receive the tie rod. On the opposite faces of the member are substantially parallel surfaces 16 and 17, which I will designate as upper and lower, and which coact respectively with the inclined surfaces 11 and 12 in the housing 7. Extending inwardly and upwardly from the surface 17 is a surface 19, which surface, when the locking member is inserted in the housing and applied to a rail, is substantially vertical or parallel to the outer edge of the rail base. Extending inwardly and upwardly from the surface 19 is a surface 20 adapted to grip the upper surface of a rail base. At the upper end of the locking member 8 the outer surface is curved, as shown at 21, this curved surface extending beyond the housing when the parts are in assembled position adjacent a rail. The lower end of the locking member is tapered and adapted to extend through the opening 14 in

the housing 7 when the device is applied to smaller sized rails.

When the housing and locking member are assembled the opening 15, which is larger than the tie rod, permits of movement of the locking member with respect to the casing and the tie rod so as to accommodate the device to rails of varying dimensions. Washers 22 and nuts 23 hold the housing and locking member in assembled position on the rail, with the locking member gripping the upper part of the rail base and the housing gripping the bottom of the rail base. The surfaces 16 and 17 of the locking member 10 coact with the surfaces 11 and 12 of the housing in such a manner as to prevent concentration at any one point in the housing of the strains caused by heavy trains passing over the rails. This I accomplish by inserting 15 in the housing the locking member to grip the top of the rail base instead of forming the housing with a hook portion to engage the said top of the rail base. The locking member also engages the outer edge of the rail base as well as the top.

In Fig. 2 I have shown my invention applied to relatively small sized rails, while in Fig. 3 I have shown it applied to rails of larger dimension. In Fig. 2 it will be noted that the locking member extends through the opening in the bottom of the housing, this adjustment of the locking member being possible by reason of the enlarged opening 15.

From the foregoing description it will be apparent that I have provided a rail gripping and shock absorbing device which may be readily adjusted to rails of varying dimensions without any change in construction; which will readily grip the rails and brace them in fixed lateral relation to one another; which will be strong and durable; and which will be inexpensive to manufacture, comprising a minimum number of parts.

Having thus fully described my invention, 45 what I claim as new and desire to secure by Letters Patent, is:

1. In a device of the character described, the combination with a tie rod, of a housing carried by the tie rod, and a locking member carried by said tie rod and enclosed partially by said housing and engaging the top of a rail base.

2. In a device of the character described, the combination with a tie rod, of a housing carried by the tie rod and engaging the bottom of a rail base, and a locking member carried by said tie rod and enclosed partially by said housing and engaging the top of said rail base.

3. In a device of the character described, the combination with a tie rod, of a housing carried by the tie rod, and a locking member carried by said housing and engaging the top and outer edge of a rail base.

4. In a device of the character described,

the combination with a tie rod, of a housing carried by the tie rod and engaging the bottom of a rail base, and a locking member carried by said housing and engaging the top and outer edge of a rail base.

5. In a device of the character described, the combination with a tie rod, of two housings carried by said tie rod, one adjacent each side of the rail base, and two locking members carried by said tie rod, one locking member for each housing by which it is partially enclosed and adapted to grip the top of the rail base, and means on the rod to draw the locking members and housings into gripping action.

6. In a device of the character described, the combination with a tie rod, of two housings carried by said rod, one adjacent each side of the rail base, two locking members, one carried by each housing, said locking members adapted to grip the top and edges of the rail base on opposite sides of the web, and means on the rod to draw the locking members and housings into gripping action.

7. In a device of the character described, the combination with a tie rod, of two housings carried by said rod, one adjacent each side of a rail base, and adapted to engage the bottom of the rail base, two locking members, one carried by each housing, said locking members adapted to grip the top and edges of the rail base on opposite sides of the web, and means on the rod to draw the locking members and housings into gripping action.

8. In a device of the character described, the combination with a tie rod, of four housings carried by said rod, one adjacent each side of each rail base of a track, four locking members carried by said tie rod, one for each housing, said locking members enclosed partially by said housing and adapted to grip the tops of each rail base on each side of the rail webs.

9. In a device of the character described, the combination with a tie rod, of a housing carried by said rod, substantially parallel inclined surfaces within said housing, a substantially flat surface on the outer part of said housing to engage the bottom of a rail base, a locking member carried by said housing, and having surfaces coacting with the inclined surfaces in said housing, said locking member adapted to grip the upper surface of the rail base, and means on the rod to draw the several parts into gripping action.

10. In a device of the character described, the combination with a tie rod, of a housing carried by said rod, substantially parallel inclined surfaces within said housing, a substantially flat surface on the outer part of said housing to engage the bottom of a rail base, a locking member carried by said housing and having surfaces coacting with the inclined surfaces in said housing, said locking

member adapted to grip the upper face and outer edge of the rail base, and means on the rod to draw the several parts into gripping action.

11. In a device of the character described, 5 a locking member having an elongated opening therein, a substantially flat upper surface terminating in a curve at its upper portion and inclined downwardly and inwardly at its lower portion, the opposite under surface extending inwardly and downwardly from a point adjacent the outer edge of the upper curved surface, thence inwardly and downwardly and thence downwardly in a 10 plane substantially parallel to the flat upper surface.

12. In a device of the character described, 15 a housing having a longitudinally extending opening therethrough, substantially parallel inclined surfaces within the housing, and a substantially flat surface on the upper part 20 of the casing at one end.

13. In a device of the character described, 25 a housing having a longitudinally extending opening therethrough, substantially parallel inclined surfaces within the housing, a substantially flat surface on the upper part 30 of the casing at one end, and an opening in the bottom of the casing at the opposite end.

14. In a device of the character described, 35 the combination with a tie rod, of two housings carried by said rod, one adjacent the outer side of each rail base of two parallel rails, two locking members carried by said rod, one for each housing, said locking members enclosed partially by said housings and adapted to grip the tops of said rail bases on the outer sides of the rail webs, and means 40 on the rod to draw the locking members and housings into gripping action.

15. In a device of the character described, 45 the combination with a tie rod screw threaded at its opposite ends, and means for surrounding said screw-threaded portions, of housings carried by said rod, and locking members, one carried by each housing, each locking member adapted to grip the top and edge of a rail base, and means on the rod for 50 drawing the locking members and housings into gripping action.

16. In a device of the character described, 55 the combination with a tie rod screw threaded at each end, means for protecting said screw threaded portions, and insulation interposed between said rod and protecting means, of housings carried by said rod and adapted to engage the bottom of rail bases, locking members, one carried by each housing, each locking member adapted to grip 60 the top and edge of a rail base, and means on the rod for drawing the locking members and housings into gripping action.

17. In a device of the character described, 65 the combination with a tie rod screw thread-

ed at each end, and a casing surrounding each screw threaded portion of said tie rod, of rail gripping devices carried by said casing, and means for retaining said casing and gripping devices in position.

70

18. In a device of the character described, the combination with a tie rod screw threaded at its ends, a casing surrounding said screw-threaded portions, and insulation interposed between said casing and said tie rod, 75 of gripping devices carried by said casing, and means for retaining said casing and gripping devices in position.

19. In a device of the character described, 80 the combination with a screw-threaded tie rod, and a casing surrounding said tie rod, of rail gripping devices carried by said casing, and means for retaining said gripping devices and casing in position.

In testimony whereof I hereunto affix my 85 signature.

JOHN G. MUELLER.
